US00D948564S

(12) **United States Design Patent** (10) **Patent No.:** **US D948,564 S**
(45) **Date of Patent:** **** Apr. 12, 2022**

(54) **DISPLAY SCREEN WITH ICON**

(71) Applicant: **Google LLC**, Mountain View, CA (US)

(72) Inventor: **Sehee Lee**, Brooklyn, NY (US)

(73) Assignee: **GOOGLE LLC**, Mountain View, CA (US)

(**) Term: **15 Years**

(21) Appl. No.: **29/782,905**

(22) Filed: **May 10, 2021**

Related U.S. Application Data

(63) Continuation of application No. 29/732,007, filed on Apr. 20, 2020, now abandoned, which is a continuation of application No. 29/717,990, filed on Dec. 20, 2019, now Pat. No. Des. 885,434, which is a continuation of application No. 29/643,565, filed on Apr. 10, 2018, now abandoned.

(57) **CLAIM**

The ornamental design for a display screen with icon, as shown and described.

DESCRIPTION

The sole FIGURE is a front view of a display screen with icon showing the new design.

The broken lines of uneven length show the display screen and form no part of the claimed design.

1 Claim, 1 Drawing Sheet
